UNITED STATES PATENT OFFICE

2,481,666

STRUT CONSTRUCTION FOR DRAFTING MACHINES

John A. Hislop, Pasadena, Calif., assignor to Vard, Inc., Pasadena, Calif., a corporation of California

Application March 5, 1946, Serial No. 652,104

3 Claims. (Cl. 33—79)

1

This invention relates to a drafting machine and has particular reference to a strut construction, whereby a drafting machine scale may be readily adjusted to different positions of orientation relative to a base line on a drawing board with which such a machine is used.

In the art of drafting, it is the common practice to employ drafting machines of the articulated arm type for the purpose of supporting one or more straight edges upon a drafting board surface in such manner that irrespective of the manipulation of the straight edges to various positions on the surface of the drafting board, the straight edges will be maintained in a definite angular relation with respect to a base line on the board.

Such machines include what is known as the "endless band and pulley" machines, wherein the orientation of the scales is maintained by providing upon the articulated arms, pulleys interconnected by means of endless steel bands, which will cause rotational movement of a scale supporting protector mechanism in equal angular but opposite directional movement corresponding to the movement of the articulated arms relative to a fixed anchor and thus maintain the scales in a fixed oriented angular position relative to the base line.

In prior constructions of this type, it has usually been the practice to provide the scale supporting mechanism with devices which may be manipulated to release the engagement between the scale support and the pulley on that arm of the machine to which it is attached, whenever it is desired to change the oriented angular relation between the scale and the base line, such mechanism being generally awkward of access to the draftsman or requiring laborious manipulation of mechanisms to effect a change in the angular relation of the scales.

It is, therefore, an object of this invention to provide a drafting machine of the character set forth, wherein adjustment of the scale to different angular positions relative to the base line may be accomplished by employing a quick release mechanism in one or both of the articulated arms, the manipulation of which will so effectively shorten the arm as to release the band on that arm from its engagement with the pulleys on that arm.

Another object of this invention is to provide a drafting machine of the character set forth, wherein the effective length of one or both of the articulated arms may be lengthened and shortened by a simple lever movement readily accessible to the fingers of the draftsman.

Another object of this invention is to provide a release mechanism of the character described, which is especially adapted to drafting machines in which the arms are of the single rod or strut type and wherein the release mechanism is interposed in the single rod in such fashion that manipulation of the release mechanism through the relatively small amount of movement will accomplish the necessary shortening of the arm to release the engagement of the band with the pulley.

Other objects and advantages of this invention will be apparent from a study of the following specifications read in connection with the accompanying drawings wherein:

Fig. 1 is a plan view of a drafting machine of the endless band and pulley type equipped with a release mechanism constructed in accordance with this invention;

Fig. 2 is a fragmentary perspective view of a portion of the strut structure comprising one of the arms shown in the machine of Fig. 1, parts being broken away to show internal mechanisms;

Fig. 3 is a longitudinal sectional view taken through that portion of the strut structure shown in Fig. 2 and illustrating the position of the parts when the strut is in its normally elongated position.

Fig. 4 is a sectional view similar to Fig. 3 but illustrating the position of the parts when the strut is in its contracted position; and

Fig. 5 is an exploded view illustrating the manner of assembly of the parts illustrated in Figs. 2, 3 and 4.

Referring to the drawings, I have illustrated in Fig. 1 a typical band and pulley type of drafting machine which comprises an articulated arm structure including a pair of arms 1 and 2, the arm 1 comprising a pair of head brackets 3 and 4 spaced from each other by means of a strut rod 5 and having a pulley 6 at one of its ends fixed to an anchor 7 which is, in turn, attached to one edge of a drafting board 8 with which the machine is to be used.

The opposite end of the arm 1 is provided with a pulley 9, an endless band of steel tape 10 being trained over the pulleys 6 and 9 in such fashion that any movement of the arm 1 about its pivot 11 at the anchor 7 will cause a corresponding rotational movement of the pulley 9 to maintain the pulley 9 in a fixed oriented angular relation with respect to the fixed pulley 6.

The arm 2 is similarly constructed of a pair of head brackets 12 and 13 spaced from each other by means of a strut rod 14, the arm 2 including

the pulley 9 at one of its ends and a pulley (not shown) at the other of its ends, over which is trained an endless band 15 by which any rotational movement imparted to the arm 2 relative to the arm 1 or any rotational movement imparted to either or both of the arms 1 and 2 relative to the fixed pulley 6 will result in a rotation of the pulley at the free end of the arm 2 corresponding to but in an opposite direction to the rotational movement of the arms 1 and 2.

The pulley at the free end of the arm 2 has secured thereto a scale support 16 which carries a pair of straight edges or scales 17 and 18.

With the structure thus far described, any movement of the scales 17 and 18 over the board 8 will result in the scales being maintained in a fixed angular position with respect to a base line on the board 8.

To adjust the angular relation between the scales 17 and 18 and such fixed base line, either the arm 1 or the arm 2 may be shortened to loosen the frictional engagement of the band associated with that arm from the pulleys comprising a part of that arm. While both of the arms of 1 and 2 may be adapted to be shortened to accomplish the release of its associated band, I prefer to provide only one of the arms with a quick release mechanism which will accomplish this result.

By referring particularly to Fig. 2, it will be observed that the rod 14 of the arm 2 is assembled with the head bracket 13 by means of a cam and follower mechanism which will permit a ready adjustment of the length of the arm between a fully extended position maintaining the band 15 in tight relation with the pulleys of the arm 2, and a contracted position in which the band is so loosened that the scale support 16 may be readily rotated without causing a corresponding rotation of the pulley 9.

The mechanism for assembling the rod 14 and the head bracket 13 preferably comprises an adapter indicated generally by the reference character 19, the adapter comprising a body portion 20 telescopically engaged within a socket 21 formed in the head 13, the adapter including a longitudinal cylindrical extension 22 adapted to be inserted into a bore 23 in the rod 14. In fact, the rod 14 may be constructed as a length of tube, the internal bore of which will snugly fit the cylindrical surface of extension 22.

The relative diameters of the body portion 20 and the extension 22 are preferably such that the end of the rod or tube 14 may telescope slightly within the socket 21 on the head 13 to thereby facilitate the manufacture and assembly of the adapter head and rod without exercising extreme care in maintaining accurate machine tolerance.

The adapter 19 is formed with a transverse slot 24 alignable with a slot 25 formed transversely through the end of the socket portion of the head 13 and through which extends a cam 26 to a position permitting it to be pivotally fulcrumed about a cross pin 27. The cam 26 preferably comprises a relatively thin blade member forming two legs 28 and 29 of a lever. The leg 28 extends longitudinally of the arm 2 when the lever is in its normal position, as shown in Figs. 2 and 3, the extreme end 30 of the leg 28 being adapted to engage the end of a cam follower formed as a plunger 31 which is slidably mounted in the body 20 of the adapter 19.

The opposite end of the plunger 31 extends

beyond the end of the adapter 19 in to engagement with the head 13 as indicated at 32, so that when the cam 26 is in the position shown in Figs. 2 and 3 the cam leg 28 will press the plunger 31 against the head 13 in such fashion as to urge the head 13 and the rod 14 outwardly with respect to each other and elongate the arm 2 to maintain the band 15 in its tight pulley engaging position.

To release the scale support 16 when making an adjustment of the angular relation of the scales with a predetermined base line, it is only necessary to rotate the cam lever 26 about its pivot 27. To facilitate this operation, the leg 29 is provided with an extension 33 adapted to extend along the upper surface of the rod 14 to such position that it may be readily grasped by the fingers of the draftsman and moved from the position shown in Figs. 2 and 3 to the position shown in Fig. 4. When the lever is in the position shown in Fig. 4, the maximum length of the cam leg 28 is no longer presented to the plunger 31 and the plunger is permitted to retract relative to the adapter 19, with the result that the adapter is moved inwardly in the socket 21, resulting in the effective shortening of the arm 2 and accomplishing the release of the engagement between the band 15 and the pulleys on the arm 2.

When the parts are in this position, the scales 17 and 18 and their support 16 may be readily rotated to a new angular position with respect to the base line, whereupon movement of the lever 26 back to its normal position so elongates the arm 22 as to re-engage the band tightly with the pulleys over which it is trained, and the drafting machine is now ready for further operation with the scales correctly oriented to a new angular position with respect to the base line.

To insure against the inadvertent loosening of the band 15 it is preferred to so shape the lever arm 28 that when the lever 26 is in its normal position a line drawn through the maximum length of the lever arm 28 and the center of the pivot pin 27 engages the end of the plunger 31 at a point above the longitudinal axis of the plunger 31, with the result that the action is an "over center" action and the tension of the band 15 will act to hold the lever 26 in its normal position.

To facilitate the manipulation of the lever 26 there may be provided lateral wings 34 extending on opposite sides of the lever extension 33, the wings being preferably curved to conform with the external curved surface of the rod or tube 14 so as to lie snugly about the rod or tube 14. Finger pieces 35 may be formed at the lower edges of the wings 34 to extend laterally thereof for more ready engagement by the fingers of the draftsman.

It will be observed therefore, that there is provided a ready mechanism for permitting the adjustment of the angular position of the scales on a drafting machine relative to a base line on the drafting board by utilizing a simple mechanism by which the effective length of one of the articulated arms may be changed so as to readily loosen the band from its pulleys and to restore the tightened relation between the band and the pulleys when the scales have been moved to their new adjusted position, the essential features of the construction being the provision of a simple mechanism by which a relatively small movement of a manipulating device, such as the lever 26, will cause a sufficient amount of contraction of the effective length of the arm to so loosen the band

75

from its pulleys as to permit the ready adjustment of the protractor or scale support to a new oriented position.

While there has been shown and described the preferred embodiment of the present invention, the same is not to be limited to any of the details of construction shown or described herein except as defined in the appended claims.

What is claimed as new is:

1. In an articulated arm drafting machine of the band and pulley type having an arm construction including, a pair of pulleys, a pair of pulley supporting heads, a band trained over said pulleys, and a single strut rod interposed between said heads to hold said pulleys in such spaced relation as to maintain frictional engagement between said pulleys and band; the improvement of an adapter interposed between said strut rod and one of said heads for telescopically assembling said rod and head, a cam on said adapter, a plunger slidable in said adapter extending in the direction of the longitudinal axis of said arm and having its ends respectively engageable with said cam and said head, and means rotatably mounting said cam on said adapter for movement between one position urging said plunger against said head and another position permitting said plunger to retract from said head to thereby effect an extension and contraction of said arm to tighten or loosen said band relative to said pulleys.

2. In an articulated arm drafting machine of the band and pulley type having an arm construction including, a pair of pulleys, a pair of pulley supporting heads, a band trained over said pulleys, and a single strut rod interposed between said heads to hold said pulleys in such spaced relation as to maintain frictional engagement between said pulleys and band, the improvement of an adapter interposed between said strut rod and one of said heads for telescopically assembling said

rod and head, a cam on said adapter, a plunger slidable in said adapter extending in the direction of the longitudinal axis of said arm and having its ends respectively engageable with said cam and said head, and pivot means extending transversely to the longitudinal axis of said arm for pivotally mounting said cam for movement between one position urging said plunger against said head and another position permitting said plunger to retract from said head to thereby effect an extension and contraction of said arm to tighten or loosen said band relative to said pulleys.

3. In an articulated arm drafting machine of the band and pulley type having an arm construction including, a pair of pulleys, a pair of pulley supporting heads, a band trained over said pulleys, and a single strut rod interposed between said heads to hold said pulleys in such spaced relation as to maintain frictional engagement between said pulleys and band; the improvement of an adapter interposed between said strut rod and one of said heads for telescopically assembling said rod and head, a cam on said adapter, a plunger slidable in said adapter extending in the direction of the longitudinal axis of said arm and having its ends respectively engageable with said cam and said head, and a handle on said cam for actuating the same, said handle being disposed relative to said cam to extend in a position parallel to said strut rod when said cam is in strut lengthening position.
